[57] **ABSTRACT**

An improved bottle closure having a reversible feature which permits alternate selection between limited (child-resistant) access or unlimited (general) access to the contents stored within the bottle.

MULTI-POSITIONABLE BOTTLE CLOSURE FOR SELECTIVE SAFETY OR GENERAL USE

BACKGROUND OF THE INVENTION

For many years, bottles and jars were fitted or adapted with closures suitable to ensure easy-access to the contents stored within.

In recent years, however, the trend in design and manufacture of the above-mentioned closures has increasingly emphasized child-protection as a principal requirement. Further, this requirement has more recently become mandated by Federal Government Regulations; wherein containers for the storage of many types of potentially toxic materials must be fitted with LIMITED-ACCESS closures, so that attempts by small children to acquire the stored materials would be summarily frustrated. Such containers are often referred to as "child-resistant" or "child-proof."

As compared to conventional types, child-resistant containers usually entail the execution of a relatively unconventional series of mechanical steps before the closures may be removed. Hence, an implied manual and visual dexterity or capability by the user becomes an inherent pre-requisite.

Instructions for opening are often printed directly on said containers, and some may be indicated as follows:

Example A

- a. ALIGN ARROWS ON CAP AND BOTTLE
- b. PUSH CAP UP WITH THUMB or,

Example B

- a. PUSH DOWN AND ROTATE CAP IN DIRECTION OF ARROWS
- b. LIFT CAP UP TO REMOVE

It should be noted that the limited access closure depicted in the drawings herein relates, generally, to Example A, above, and also to subject matter of the Horvath U.S. Pat. No. 3,627,160; though the illustrated showing is not intended to be restrictive, and may take other forms, without departing from the spirit and the scope of the instant invention.

While child-resistant containers are successful in accomplishing their intended purpose toward small children, it has been found that certain adult groups have like-wise experienced at least a minor degree of frustration in opening them. For example:

- a. Arthritis, or others, may lack the required manual dexterity.
- b. Heart patients may panic if required medication is not immediately accessible; thus compounding their particular medical problem.
- c. The visually infirm may find some alignment requirements to be beyond their physical capabilities.
- d. Those endowed with a lesser than average degree of mechanical aptitude may also experience difficulty.

SUMMARY OF THE INVENTION

It is therefore an object of this invention to provide a dual-mode container closure which permits the responsible user to select either limited (child-resistant) access to the stored materials, or unlimited (general) access to same. Whereas, households with vulnerable small children to protect, would obviously tend to select and use the limited access portion of the inventive

closure; childless households could be free to utilize the unlimited access portion, at their option.

A further object of this invention is to provide a container closure which presents expanded gripping and leverage surfaces (when used in the limited access mode) without loss of any of its child-resistant capabilities. Whereas, households containing both small children PLUS elderly or infirm adults, may be assured that each group will be served to the intended extent.

BRIEF DESCRIPTION OF THE DRAWINGS

Referring now to the drawings wherein:

FIG. 1 is a pictorial view of the inventive closure.

FIG. 2 is a side elevation (partially cut away) showing the inventive closure in the unlimited (general) access mode.

FIG. 3 is a side elevation showing the inventive closure in the limited (child-resistant) access mode.

FIG. 4 is a sectional view taken along line 4-4 of FIG. 3.

FIG. 5 is a partial pictorial view showing the neck portion of a bottle adapted to receive and secured one form of limited access closure.

DETAILED DESCRIPTION OF THE DRAWINGS

Referring again to the drawings, wherein like reference numerals designate like or corresponding parts throughout the several views; there is shown in FIG. 1 a preferred embodiment of the inventive reversible closure.

Closure 10 is comprised of stopper (or plug) portion 12 which may be integrally formed at flange 14D with cap (or skirt) portion 14. Removable disc 15, which rests atop inwardly projecting lugs 14A and 14B, fits snugly within cap 14 to form a secondary storage compartment within closure 10 itself, if desired, when said closure is utilized in the unlimited access mode of FIG. 2. Such an additional storage compartment would be especially useful for the daily storage of medicinal dosages. Of course, disc 15 must be removed when said closure is being utilized in the limited access mode of FIGS. 3 and 4.

As indicated in FIG. 3, stopper 12 represents the unlimited access portion of the closure 10, and cap 14 represents the limited access portion.

To attain the unlimited access (general) mode, as shown in FIG. 2, stopper 12 is inserted snugly into aperture 20A of bottle 20 until flange 14D becomes fully seated on mouth 20B. When this is accomplished, the cotton filler material 34 becomes downwardly compressed against pills (tablets, capsules or the like) 32 in the storage area of bottle 20; thus, allowing a minimum of vibration between pills 32 during shipment. Closure 10 may, of course, be pulled upwardly for easy removal from bottle 20.

In the limited access (child-resistant) mode, as shown in FIG. 3, cap portion 14 is placed over the neck portion of bottle 20 and pushed downwardly until lugs 14A become positioned in snug contact with the underside of partial locking rim 22 on bottle 20. Concurrently, flange 14D and bottle mouth 20B co-act to form a tight seal between cap 14 and bottle 20.

A single opening occurs along the radial axis of locking rim 22 at point 20C on bottle 20. Solid rim 23, positioned below rim 22, contains on its surface an arrow symbol 23A, which coincides with the location of point 20C.

Lug 14B is located along the same radial plain within cap 14 as corresponding lugs 14A. An arrow shaped tab 14C, on the outer periphery of cap 14, coincides with the location of lug 14B.

A disalignment of arrows 14C and 23A would indicate that lugs 14A and 14B are secured under locking rim 22, hence, the removal of cap 14 from bottle 20 cannot occur.

Removal of cap 14 from bottle 20 may be accomplished, only, by rotating said cap or bottle until arrows 14C and 23A are aligned, thus freeing lug 14B for movement away from rim 22. Then, an obliquely upward thumb pressure on either arrow 14C or stopper 12 will disengage the remaining lugs 14A, still secured below rim 22, and closure 10 may be freely separated from bottle 20.

It should be noted that application of thumb pressure to stopper 12, rather than arrow tab 14C, offers an added gripping area and mechanical advantage; hence providing an easier closure 10 removal for individuals with manual dexterity handicaps, such as Arthritis or the like.

In the foregoing drawings and specification, there is specifically disclosed only the preferred embodiment of the invention, though it will be readily realized that various modifications may be made without departing from the spirit and scope of the inventive concept as defined in the accompanying claims.

What is claimed is:

1. A multi-positionable closure for a container, the container having an access opening formed thereon, the improvement comprising:

4
a first cap means on said closure having formed thereon a securing surface for sealingly mating with said access opening;

a second cap means extending from said first cap means having formed thereon a securing surface for lockingly mating with said access opening; an elongated gripping surface on said first cap means cooperating with the securing surface on said second cap means by providing leverage capability to assist in unlocking said second cap means from said access opening.

2. A multi-positionable closure according to claim 1, further comprising:

said first cap means including a first cylinder, being elongated and contiguously attached to a plate member to close the one end of said first cylinder; at least a portion of the remaining surfaces on said first cylinder being formed to sealingly mate with said access opening.

3. A multi-positionable closure according to claim 2, further comprising:

said second cap means including a second cylinder contiguously attached to said plate member to close the one end of said second cylinder; at least a portion of the remaining surfaces on said second cylinder being formed to lockingly mate with said access opening.

4. A multi-positionable closure according to claim 3, further comprising:

said first and second cylinders being coaxially aligned; a disc member being releasably insertable into said second cylinder opposite said plate member to selectively form a closed storage chamber within said second cylinder.
